UNITED STATES PATENT OFFICE.

ALFRED W. JANSEN, OF CHICAGO HEIGHTS, ILLINOIS.

FIRELESS COOKER.

1,021,679.

Specification of Letters Patent. Patented Mar. 26, 1912.

Application filed November 3, 1911. Serial No. 658,427.

To all whom it may concern:

Be it known that I, ALFRED W. JANSEN, a citizen of the United States, residing at Chicago Heights, in the county of Cook and State of Illinois, have invented certain new and useful Improvements in Fireless Cookers; and I do hereby declare the following to be a full, clear, and exact description of the invention, such as will enable others skilled in the art to which it appertains to make and use the same.

This invention relates to fireless cookers and has for an object to provide a cooker in the form of an insulated cylinder, both ends of which can be removed for the purpose of cleaning or other purposes.

A further object of the invention is to provide improved construction of the cylindrical portion of the cylinder from which both the top and bottom are removable.

With these and other objects in view the invention comprises certain novel constructions, combinations and arrangements of parts as will be hereinafter more fully described and claimed.

In the drawings:—Figure 1 is a view in side elevation of a cooker made in accordance with the present invention. Fig. 2 is a vertical, diametrical, sectional view of the improved cooker. Fig. 3 is an inverted plan view of the cooker. Fig. 4 is a transverse sectional view taken on line 4—4 of Fig. 2, with part of the removable bottom broken away.

Like characters of reference indicate corresponding parts throughout the several views.

The improved cooker which forms the subject matter of this application comprises an outer shell or casing 10 and an inner cylinder 11 with the space between such shell and cylinder filled with heat insulating material of any approved form, as conventionally shown at 12 in Fig. 2.

The outer shell and inner cylinder are secured together by means of forming flanges 13 and 14 upon the opposite ends of the cylinder which engage annular rings 15 and 16 respectively. The annular ring 15 is secured

to the casing 10 by employing a ring 17, preferably ornamental in nature, and turning the upper edge of the casing 10 inwardly, as shown at 18, such inturned edge being clamped between the annular ring 15 and the ornamental ring 17.

At the lower end an ornamental base 19

is employed and the casing 10 is provided with a bead 20 forming a groove or furrow to receive the inner edge of the ornamental base, as indicated at 21, with a bolt 22 passed through such ornamental base and the annular ring 16 so that the edge of the casing 10 is clamped between the base 19 and the ring 16. In this manner the casing 10 and the cylinder 11 are clamped firmly and rigidly together.

The ring 15 is provided with an annular rabbet to receive a flange 23 of an insulating cover 24 which sets into the cylinder 11 and also to receive an ornamental cover 25 which, being spaced away from the insulated cover 24, provides a dead air space which also adds to the insulating effect of the cover.

At the lower end the cylinder is provided with an insulating removable bottom 26 which is provided with a flange 27 fitting into an annular recess in the ring 16 and removably secured therein by bolts 28 which also serve to position the brackets 29 upon which are mounted casters 30, such frame and casters being removable with the bottom by removing the nuts from the bolts 28.

It will be apparent from the construction that the upper end of the cooker is opened in the usual and ordinary manner by the removal of the cover 25 and the inner insulated cover 24. This is for the ordinary use when the cooker is in operation. For cleaning purposes and the like, the bottom may also be removed from the lower end of the cylinder by removing the nuts from the bolts 28 and releasing the removable bottom 26, which leaves a cylinder open at both ends, readily and easily cleaned.

I claim:—

1. In a fireless cooker, an inner cylinder having outturned flanges, an outer shell having a bead formed at its lower edge, a base engaged within the groove formed at the bead, an annular ring clamping the base and shell and engaging the flange at one end of the cylinder, and an annular ring at the other end engaging the other flange of the cylinder and the upper end of the casing.

2. In a fireless cooker, an inner cylinder having outturned flanges at its opposite ends, an outer casing having a bead formed at its lower edge producing a furrow upon its outer surface, an annular base engaged within the furrow, an annular ring disposed between the cylinder and the casing and

rigidly secured to each, and an annular ring engaging the cylinder at its opposite end and clamping the upper end of the casing.

3. In a fireless cooker, inner and outer cylinders spaced apart and having heat insulating material therebetween, a base formed upon the outer cylinder and extending downwardly to serve as a support, a heat insulating bottom member removably insertible in the inner cylinder, supporting

casters carried by the removable bottom, and a heat insulating top member adapted to be inserted in the top of the inner cylinder.

In testimony whereof I affix my signature in presence of two witnesses.

ALFRED W. JANSEN.
